UNITED STATES PATENT OFFICE.

WILLIAM A. PRINGLE, OF NIAGARA FALLS, NEW YORK, ASSIGNOR TO THE CARTER-CRUME COMPANY, LIMITED, OF NIAGARA FALLS, NEW YORK, A CORPORATION OF CANADA.

DELIVERY MECHANISM FOR PRINTING-PRESSES.

1,010,520.

Specification of Letters Patent.

Patented Dec. 5, 1911.

Application filed August 4, 1908. Serial No. 446,839.

To all whom it may concern:

Be it known that I, WILLIAM A. PRINGLE, a citizen of the United States, residing at Niagara Falls, in the county of Niagara and State of New York, have invented certain new and useful Improvements in Delivery Mechanism for Printing-Presses, of which the following is a full, clear, and exact description, such as will enable others skilled in the art to which it appertains to make and use the same.

This invention relates to printing mechanism, and more particularly to mechanism of this character adapted for delivering sheets cut from one or more traveling webs upon which printing has been effected.

One of the objects of the invention is to provide an improved mechanism of the above character such that the severed portions of the web are delivered in a more efficient manner from the cutting mechanism than it has been possible to perform such operation in delivery mechanism as hitherto constructed.

Another object thereof is to provide mechanism wherein the severed sheets will not interfere with one another when they are being delivered from the cutting mechanism, and wherein they can be conveniently piled one upon the other in superimposed relation.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings wherein is illustrated one of the various possible embodiments of my invention, Figure 1 is a view in side elevation thereof. Fig. 2 is a top plan view. Fig. 3 is a view in plan upon an enlarged scale showing the corrugated feed rolls for feeding the severed sheets. Fig. 4 is a vertical sectional view taken longitudinally of the mechanism. Fig. 5 is a view in elevation of a detail of construction.

Similar reference characters refer to similar parts throughout the several views of the drawings.

Referring now to the drawings 1 denotes

a portion of the frame of a printing press 55 and 2 is a bed or table upon which sheets 3 which have been cut from traveling webs 4 are adapted to be deposited in superimposed relation. In the present instance I have shown the mechanism adapted for operating upon two traveling webs, upon which printing has been effected by the various cylinders of the press, which cylinders are not shown in the present drawings. It will be understood, however, that a single web or a greater number of webs than shown herein may be operated by the present mechanism. Feed rolls for the webs are indicated diagrammatically at 5 and 6 and 7 and 8 respectively. Feed roll 7 is positively driven 70 at a given peripheral velocity by gear 10, a gear 11 forming a connection between gear 10 and a gear 12 which drives feed roll 5 at a peripheral velocity equal to that at which feed roll 7 is driven. The feed rolls 6 and 75 8 are rider or idler rolls which are spring-pressed into engagement with the positively driven rolls 5 and 7 respectively, and hold the traveling webs in close contact therewith.

Journaled in an upward extension 9 of the frame work is a cylinder 13 provided with a knife 14 which co-acts with a knife 15 fixed in the frame, said knives co-acting at each rotation of cylinder 13 to sever sheets 85 from the webs which are being delivered by the feed rolls.

16 and 17, respectively, are corrugated feed rolls suitably journaled in eccentric bearings provided in standards 18 erected 90 upon bed 2. The corrugated portions 20 and 21 of these rolls are spaced apart as clearly shown in Fig. 3 and arranged in staggered relation. The function of these rolls, which are driven at a greater peripheral velocity 95 than the velocity of the traveling web, is to grasp the end of the web passing between the cutters 14 and 15 during the revolution of cylinder 13 and hold the same in a taut condition during the cutting operation as 100 clearly shown in Fig. 1 of the drawings. When the knives 14 and 15 have severed the sheets from the webs said sheets are moved forward from the knives at the speed at which the rolls 16 and 17 are running, thus 105 opening a space between the end of the web and the ends of the cut sheets. The corrugations of the two rolls sustain such rela-

tions to each other that the sheet is not pinched between the rollers, but is merely crimped by the corrugations and carried forward by friction. The rolls 16 and 17 are 5 highly polished, and, therefore, leave no mark upon the sheet.

Knife cylinder 13 is provided with a gear 22 which is driven by a gear 23, the latter being driven from gear 10 by an intermediate gear 24. Gear 23 also operates to drive cylinder 16, which in turn drives the cylinder 17, at an equal peripheral velocity.

The cut sheets which, after their delivery from cylinders 16 and 17, tend to fall by 15 gravity upon table 2, are engaged and depressed by fingers 25 which are carried upon a shaft 26 journaled in arms 27 extending upwardly from table 2 and bolted thereto.

An arm 28 fixed upon shaft 26 extends upwardly therefrom and is connected with a reciprocating rod 30, which is suitably guided in a bracket or stop 31 and is similarly guided at its opposite end in a standard 32.

A spring 33 coiled about rod 30 is interposed between stop 31 and a collar 29 fixed upon rod 30, and this spring, through rod 30, arm 28 and shaft 26, causes the fingers 25 to move in a downward direction. Rod 30, at its free end, is provided with an anti-friction roller 34 which rides upon the periphery of a member 35 fixed upon the shaft of cylinder 13, said member being provided with a sharply cut-away cam portion 37. During the rotation of cylinder 13 this cam portion is engaged by anti-friction roller 34, such engagement allowing spring 33 to depress the fingers 25 as above explained. It will, therefore, be seen that upon each rotation of cylinder 35 the fingers 25 will be vibrated downwardly to depress the cut sheets 40 upon the table 2.

Having thus described the construction of this embodiment of my invention the operation thereof which to a large extent should be obvious is substantially as follows. Upon each rotation of cylinder 13 portions of the webs 4 are projected over knife 15 the ends thereof being received between the cylinders 16 and 17 which operate to hold the webs in 50 taut condition while the knives 14 and 15 are co-operating to sever the sheets. After the knives have severed the sheets said sheets are moved forward from the knives at the speed at which rolls 16 and 17 are running, 55 and open up a space between the end of the web and the end of the sheet which has been cut off as above explained. This gives time for the "knock-down" fingers 25 to depress the sheet upon the table and to return to their raised positions before a second series 60 of sheets has been delivered from the rolls 16 and 17.

It will accordingly be seen that I have provided mechanism well adapted to attain 65 among others all the objects above pointed

out in an extremely simple yet efficient manner. Owing to the fact that the feeding of the sheet from the cutting mechanism is accelerated there is no danger of the machine being clogged or rendered inoperative by 70 succeeding sheets being delivered above the "knock-down" finger before they have assumed their normal positions. The web, moreover, being kept at taut condition during the operation of the knives, the cutting 75 operation is facilitated.

While I have shown my invention as applied to a press of the above type it will be understood that it may be adapted to other forms of presses or, in fact, to any type of 80 apparatus where it is desired to sever webs into sheets.

As many changes could be made in the above construction and many apparently widely different embodiments of this invention could be made without departing from the scope thereof, it is intended that all matter contained in the above description or shown in the accompanying drawings shall be interpreted as illustrative and not in a 85 limiting sense. It is also to be understood that the language used in the following claims is intended to cover all of the generic and specific features of the invention herein described and all statements of the scope of 90 the invention which, as a matter of language, might be said to fall therebetween.

Having described my invention, what I claim as new and desire to secure by Letters Patent is:

1. In delivery mechanism for printing presses, in combination, means for feeding a web, a fixed knife, and a movable knife co-operating to sever sheets from the web, means for grasping the several sheets and feeding the same from the cutting means, a table, spring actuated means operatively associated with said severing means for delivering the severed sheets upon said table in superimposed relation, and means adapted to permit the actuating of said spring.

2. In delivery mechanism for printing presses, in combination, a fixed cutter, a cylinder carrying a movable cutter which is adapted to co-act with said fixed cutter to 115 sever sheets from a traveling web, a plurality of rolls for feeding the web to the cutters, a plurality of rolls for grasping sheets severed from the web, said last mentioned rolls being driven at a greater peripheral velocity than that of the first mentioned rolls, a table, and means operatively associated with said cutting means for delivering the sheets upon said table in superimposed relation.

3. In delivery mechanism for printing presses, in combination, means for feeding a web, means for severing the web into sheets comprising a stationary cutter and a rotary cutter, and a pair of circumferen- 130

tially corrugated rolls adapted to maintain the web in taut condition while the same is being severed.

4. In delivery mechanism for printing presses, in combination, means for cutting sheets from a traveling web, feeding means for said web arranged at one side of said cutting means, feeding means for the severed portions of the web arranged at the other side of said cutting means, said last mentioned feeding means being driven at a greater peripheral velocity than the first mentioned thereof, whereby a space is provided between the ends of the cut sheets and the end of the traveling web, a table, and means operatively associated with said cutting means for depositing the sheets upon said table in superimposed relation.

5. In delivery mechanism for printing presses, in combination, a fixed cutter, a rotary cylinder carrying a cutter adapted to co-act with the fixed cutter to cut sheets from a traveling web, feed rolls for delivering the web to said cutters, a pair of corrugated feed rolls adapted to engage the web and hold the same taut while being cut, said last mentioned rolls being adapted to move the cut sheets from the cutters at a speed greater than that at which the web is fed thereto, a table, and a plurality of oscillatory fingers adapted to engage the sheets and deposit them upon said table in superimposed relation.

6. In delivery mechanism for printing presses, in combination, a fixed cutter, a rotary cylinder carrying a cutter adapted to co-act with the fixed cutter to cut sheets from a traveling web, feed rolls for delivering the web to said cutters, a pair of corrugated feed rolls adapted to engage the web and hold the same taut while being cut, said last mentioned rolls being adapted to move the cut sheets from the cutters at a speed greater than that at which the web is fed thereto, a table, a plurality of oscillatory fingers adapted to engage the sheets and deposit them upon said table in superimposed relation, and means driven from said knife cylinder for oscillating said fingers.

7. In delivery mechanism for printing presses, in combination, a fixed cutter, a rotary cylinder carrying a cutter adapted to co-act with the fixed cutter to cut sheets from a traveling web, feed rolls for delivering the web to said cutters, a pair of corrugated feed rolls adapted to engage the

web, and hold the same taut while being cut, said last mentioned rolls being adapted to move the cut sheets from the cutters at a speed greater than that at which the web is fed thereto, a table, a plurality of oscillatory fingers adapted to engage the sheets and deposit them upon said table in superimposed relation, a reciprocating rod operatively connected to said fingers, a cam operatively associated with said rotary cylinder for moving said rod in one direction, and a spring for moving said rod in the opposite direction.

8. In delivery mechanism for printing presses, in combination, a fixed cutter, a rotary cylinder carrying a cutter adapted to co-act with the fixed cutter to cut sheets from a traveling web, means for delivering the web to said cutters, means to feed the cut sheets from said cutters, a table, oscillating means adapted to engage said cut sheets and deposit them upon said table in superimposed relation, reciprocatory means for actuating said oscillating means, means operatively associated with said rotary cylinder for moving said reciprocatory means in one direction, and means for moving the same in the opposite direction.

9. In delivery mechanism for printing presses, in combination, web-cutting means comprising a fixed cutter and a movable cutter, a rotatably mounted cylinder upon which said movable cutter is mounted, feed rolls for delivering the web to said cutters, and a pair of corrugated feed rolls for receiving the web upon the other side of said cutters, the corrugations of said rolls being spaced apart and arranged in staggered relation, said corrugated rolls being driven at a peripheral velocity greater than that at which the other feed rolls are driven, a table, oscillatory fingers adapted to engage the sheets, whereby the sheets are placed one upon the other in superimposed relation, a reciprocatory rod connected with said fingers, a cam mounted upon said cylinder for moving said rod in one direction, and a spring engaging the rod adapted to move the same in an opposite direction.

In testimony whereof I affix my signature, in the presence of two witnesses.

WILLIAM A. PRINGLE.
